UNITED STATES PATENT OFFICE.

ELEAZER KEMPSHALL, OF SHARON, MASSACHUSETTS.

DIE FOR APPLYING PLASTIC MATERIAL TO LACING-HOOKS.

SPECIFICATION forming part of Letters Patent No. 532,204, dated January 8, 1895.

Application filed October 17, 1894. Serial No. 526,137. (No model.)

To all whom it may concern:

Be it known that I, ELEAZER KEMPSHALL, of Sharon, in the county of Norfolk and State of Massachusetts, have invented certain new and useful Improvements in Dies for Applying Plastic Material to Lacing-Hooks, of which the following, taken in connection with the accompanying drawings, is a specification.

My invention relates to dies for applying plastic material to lacing hooks; and it consists in certain novel features of construction, arrangement and combination of parts which will be readily understood by reference to the description of the drawings and to the claims hereto appended and in which my invention is clearly pointed out.

Figure 1 of the drawings is an end elevation of a set of dies embodying my invention. Fig. 2 is a vertical section of the same on line 2, 2 on Fig. 1. Fig. 3 is a plan of the bed plate and the removable bed dies. Fig. 3^a is an edge view of the head supporting bed die. Fig. 4 is a transverse section of the same on line 3, 3, on Figs 3^a and 5. Fig. 5 is an inverted plan of the same. Fig. 6 is an edge view of the neck supporting die. Fig. 7 is a transverse section of the same on line 4, 4, on Figs. 6 and 8. Fig. 8 is an inverted plan of the same. Fig. 9 is a central vertical section of a lacing hook with its head covered with plastic material by my improved dies, but drawn to an enlarged scale, and Fig. 10 is a sectional elevation of the dies with the metal hook in position therein.

In the drawings A is the bed-plate having formed in its upper face a shallow transverse groove *a* in which are fitted side by side the head supporting and shaping die *b* and the neck supporting die plate *c*, and said bed-plate has formed therein beneath the die plates *b* and *c* the perforation *d* to receive the shank *e* of the lacing hook, and also has set in its upper side the guide studs *f*, *f*, and register pin *g* as shown.

The die plate *b* has formed in its upper surface an annular shallow recess *h* of a depth equal to the thickness of the plastic material that it is desired to have beneath the metal head of the hook. In the center of the recess *h* is an upwardly projecting boss or hub *i* the upper surface of which is on a level with the upper surface of the die-plate *b*. The plate *b*

also has formed in its under side directly beneath the recess *h* the recess *j* to receive the flange *e'* of the metal hook the neck of said hook passing around the rounded thin edge of metal *k* between said two recesses.

The plate *c* has formed in its edge next to the plate *b* an inclined curved surface *c'* to fit against the curved neck of the hook to be operated upon, and both plates *b* and *c* have formed in their contiguous edges semi-circular notches to engage the registering pin *g*.

B is a vertically movable plate fitted to and movable on the guide studs *f*, *f*, and has set 65 therein the movable head shaping die *C* as shown.

The operation of my invention is as follows: The metal hook, the head of which is a plain disk of metal having parallel upper and lower sides, is slipped upon the thin edge *k* of the plate *b*, with the under side of the head *e*² thereof resting upon the boss or hub *i* and the flange *e'* of said hook within the recess *j*. The plate *b* is then placed in the groove *a* of the 75 bed plate *A* with the semi-circular notch in the edge thereof engaging the side of the pin *g*. The plate *c* is then placed in position in the groove *a* beside the plate *b*, with the semi-circular notch in its edge in engagement with 80 the pin *g*, and the curved surface *c'* bearing against the neck *e*³ of the lacing hook, as shown in Fig. 10. A piece of pyroxyline or like material of sufficient size and heated to bring it into a plastic state is placed upon the upper side of the metal head of the hook beneath 85 the die *C* which is then moved downward upon said plastic material, with sufficient pressure to impart the desired shape to the top of the head, and force the plastic material beneath 90 said head, so as to fill the space between the under side of the metal head of the hook and the bottom of the recess *h* up to and surrounding the boss or hub *i*. The die *C* is then lifted, the plates *b* and *c* are removed from 95 the groove *a* and separated, when the hook can be removed from plate *b* by lifting it until the boss or hub *i* is removed from the covering material and then moving said hook in a direction parallel to the top and bottom 100 faces of the plate *b*. By this construction of the dies the metal heads of lacing hooks can be covered with a plastic material upon the bottom as well as the top, without the trouble

of forming eyelets, perforations, indentations, or projections on said heads.

What I claim as new, and desire to secure by Letters Patent of the United States, is—

- 5 1. In dies for covering the heads of lacing-hooks, the combination of a head-supporting die, an upwardly projecting boss or hub for the head of the hook to rest upon, a neck supporting die-plate, and a vertically movable pressure die for shaping the plastic material.
- 10 2. In dies for covering the heads of lacing-hooks the combination of a bed plate provided with a perforation to receive the shank of the hook; a pair of hook holding plates detachably secured to said bed plate one of which is provided with an upper annular recess surrounding a central boss or hub upon which the metal head of the hook is supported, and a lower recess to receive the flange or head of the shank; and a vertically movable pressure die for shaping the plastic material.

3. The combination of the bed-plate A provided with the groove *a* and the perforation *d*; the registering pin *g* set in said plate; the plate *b* provided with the recesses *h* and *j* 25 and the hub or boss *i* and a semicircular notch to engage the pin *g*; the plate *c* provided with a similar notch to engage said pin *g* and the curved surface *c'* to bear upon and support the neck of the hook to be operated upon; and the vertically movable die C all constructed, arranged and operating substantially as described.

In testimony whereof I have signed my name to this specification, in the presence of 35 two subscribing witnesses, on this 15th day of October, A. D. 1894.

ELEAZER KEMPSHALL.
